Des. 235,589
Patented July 1, 1975

235,589

ARCHERY FINGER GLOVE

George D. Birnie, Pine Bluff, Ark., assignor to Brunswick Corporation, Skokie, Ill.

Filed Feb. 28, 1973, Ser. No. 336,540

Term of patent 14 years

Int. Cl. D2—06

U.S. Cl. D2—361

FIG. 1 is a perspective view of the back of an archery finger tab showing my new design;

FIG. 2 is a palm side view thereof; and

FIG. 3 is a side elevational view.

I claim:

The ornamental design for an archery finger glove, substantially as shown and described.
